UNITED STATES PATENT OFFICE.

SIMEON C. LAWLOR, OF CHICAGO, ILLINOIS.

WRINGING APPARATUS.

Application filed November 12, 1920. Serial No. 423,573.

To all whom it may concern:

Be it known that I, SIMEON C. LAWLOR, a citizen of the United States, residing at Chicago, in the county of Cook and State 5 of Illinois, have invented certain new and useful Improvements in Wringing Apparatus; and I do hereby declare the following to be a full, clear, and exact description of the invention, such as will enable others 10 skilled in the art to which it appertains to make and use the same.

This invention relates to improvements in wringing apparatus, and more particularly to such as is especially adapted for use in 15 connection with scrubbing pails and like containers.

The object in view is the improvement of such apparatus as is disclosed in my United States Letters Patent No. 1,085,346, dated 20 January 27, 1914.

A more detail object is the provision of wringing means susceptible of easy and quick application and removal to and from a scrubbing pail or other like container, and 25 a still further object is the construction of a wringer roll in such form as to insure effective gripping of a mop or like article being wrung so as to prevent slipping of the rollers and failure in the wringing operation.

With these and further objects in view 30 as will in part hereinafter become apparent and in part be stated, the invention comprises certain novel constructions, combinations and arrangements of parts as subsequently specified and claimed.

In the accompanying drawings,—

Figure 1 is a perspective view of an apparatus embodying the features of the invention, the parts being shown as applied 40 to a pail.

Figure 2 is a plan view thereof on a slightly enlarged scale.

Figure 3 is a front elevation, a fragment 45 of the pail being shown in section, and parts being broken away and other parts being shown in section.

Figure 4 is an end view of the parts detached, parts of the clamping means being broken away.

Figure 5 is a similar view of the opposite 50 end of the apparatus, the movable roller being shown in dotted lines in its raised position.

Figure 6 is a detail section taken on the 55 plane indicated by line 6—6 of Figure 2.

Figure 7 is an enlarged, detail, perspective

view of the movable wringer roll and its hinged bearing detached, fragments of the roll being shown broken away for disclosing the construction of the edges of the gripping 60 slots.

Figure 8 is a detail section taken on the plane indicated by line 8—8 of Figure 4.

Figure 9 is a vertical section taken on the plane indicated by line 9—9 of Figure 2. 65

Figure 10 is a perspective view of the pivoted hinge plate of the movable roller detached and shown on an enlarged scale.

Figure 11 is an enlarged, transverse section through the slotted wringer roll detached, the parts being shown on an enlarged scale. 70

Figure 12 is a detail plan of one of the stop plates detached.

Referring to the drawings by numerals, 75 1 indicates a pail of the type commonly used for scrubbing purposes. The present improved wringing apparatus is adapted to be detachably clamped in operative position on the top of the pail 1, and to this end 80 brackets 2, 2, are secured to the pail. Each bracket 2 consists of a plate having a hook at its upper end adapted to overhang and engage the upper edge of the pail 1, each plate having an outstanding arm 3 engaged 85 by a retaining bolt or rod 4 which extends to the lower end of the pail and is formed into a tread 5. The lower portion of each rod 4 extends through an outstanding arm of a bracket 6, which bracket is formed with a 90 hook underhanging the lower edge of pail 1, and the tread 5 of each rod 4 is formed by bending the rod into a loop and extending the return portion in position for the free end thereof to abut against the under face 95 of the outstanding arm of the respective bracket 6. The loop which constitutes the tread 5 is bent or positioned to extend nearly at right angles to the line of rod 4, so that the treads 5 are adapted to rest upon or ad- 100 jacent to the floor when the pail 1 is resting on the floor, and the operator may place his feet on treads 5 for holding the pail and parts carried thereby against movement during operation. The upper end of each rod 105 4 is engaged by a nut 7 arranged above the respective arm 3 so as to enable the brackets 2 and 6 to be drawn toward each other and thereby firmly clamp the pail between the brackets. Each arm 3 extends beyond its respective rod 4 and its outer portion is 110 penetrated by a bolt 8, which extends up-

wardly and passes through a longitudinal slot in a bar 9. A wringer frame 10 is mounted above the pail 1, and the bars 9 extend through the respective side plates 11, 11, of the frame 10, and are clamped to the frame at the inner portions of bars 9 by bolts 12, 12, one bolt 12 extending through the slot of each bar 9 and through a transverse plate of frame 10. A nut 13 is 5 threaded onto the upper end of each bolt 8, above the respective bar 9, so as to enable stressing or clamping the bar toward the respective arm 3 by threading the respective nut 13 downward. Thus the frame 10 may 10 be clamped against the upper edge of pail 1 by means anchored to both the top and bottom of the pail.

To avoid possible shifting of the frame 10, additional securing means are provided 20 consisting of a pair of clamps at the front and a second pair of clamps at the rear portion of the ends of the frame 10. That part of frame 10 which is nearest to the operator when he stands with his feet on treads 5 is 25 arbitrarily called the front for facility of identification.

The pair of brackets at the front portion of the frame consists of plates 14, best seen in Figures 2 and 6, arranged beneath the 30 frame 10 and each provided at its outer end with a hook 15 adapted to fit about the bead at the upper edge of the pail 1. A corner web or plate 16 is arranged at each end of the frame 10 in the respective corner 35 of the front portion thereof, and, in fact, forms a part of the frame, being permanently fixed to the side and end bars of the frame. Each plate 14 underlies a portion of the respective web 16, the web being 40 formed with a slot 17 through which extends a clamping bolt 18, which bolt also extends through the respective plate 14 and is provided with an appropriate nut beneath the web for enabling the plate 14 to be 45 firmly clamped to the web. A bolt 19 is also passed through each plate 14 and through the adjacent portion of frame 10, and is provided at its upper end with a wing nut 20, the bolt 19 being designed to function 50 as a pivot for the respective plate 14 so that the plate 14 may be adjusted angularly by manipulation of bolt 18 along slot 17, whereby the hook 15 of each plate 14 may be caused to assume that angle best 55 adapted to enable it to effectively engage the bead of the upper margin of pail 1. Each plate 14 is slotted longitudinally, as indicated at 14' in Figure 6, and the bolts 18 and 19 are passed through the slot of the plate so as to enable the hook 15 to be moved 60 inward or outward for adjustment radially with respect to the pail 1 in addition to the angular adjustment.

65 The pair of brackets at the rear of the frame 10, as best seen in Figures 2 and 9,

consists of plates 21, 21, and their connected parts. Each plate 21 is slotted longitudinally and extends beneath the rear portion of frame 10 and carries a bolt 22 which extends through the slot and through an aperture in frame 10, and is provided with a wing nut 23 at its upper end for clamping the respective plate 21 to the frame 10 and holding it in rigid engagement therewith at any given adjusted position. The outer end of each plate 21 is formed into an eye 24 in which is hinged a link 25 whose free or pendent portion is pivoted to an operating lever 26. The lever 26 is in turn pivoted to outstanding eyes 27 fixed to a plate 28 which rests against the outer face of pail 1, and, when the parts are in their clamped position, has its upper edge firmly engaging the under portion of the upper marginal bead of pail 1. The link 25 engages lever 26 intermediate its ends, while the lever is pivoted at one end to the eyes 27, so that an eccentric clamping action is produced when the lever 26 is swung downward until the lever-engaging end of link 25 is moved 70 beyond the pivotal connection between lever 26 and eyes 27. The resultant eccentric movement of link 25 causes the eye 24 to be moved toward the brackets 27, so that the relative movement of the parts causes the plate 28 to move upward until its upper edge engages the upper marginal bead of pail 1 and causes the plate 21 to be clamped firmly down against said bead. To release the engagement of plate 21, it is only necessary to lift the lever 26 and to facilitate such action, a thumb piece or other appropriate handle 29 is provided for the lever 26. The lever 26 may assume various detail forms, one of which 75 is shown, consisting of a stamping producing two side plates forming two sections of lever 26 connected by the thumb piece 29. It will be understood, of course, that the relative movement between the eye 24 and the plate 28 will correspond exactly with the distance between the pivot of lever 26 to the eyes 27 and the pivot of link 25 to lever 26, and the parts are proportioned for insuring sufficient movement to enable the 80 plate 28 to move freely to and from the clamping position.

The action of the rear pair of clamps in holding the frame 10 against relative movement with respect to the pail 1 depends upon the clamping action and upon the fact that one of the clamps is balanced against the other so that movement of the frame longitudinally in one direction is prevented by one of the clamps while movement in the opposite direction is prevented by the other, and this is ordinarily amply secure. But in case the operator should desire further protection against possible longitudinal movement, a plate 37 may be provided for 85 90 95 100 105 110 115 120 125 130

each clamp and is slotted longitudinally. Each plate 37, when used, is arranged beneath the under face of plate 21, and the bolt 22 is passed through the slot of the 5 plate 37. The end of plate 37 adjacent the wall of pail 1 is turned or bent downward producing the flange 37' forming an abutment which may be adjusted by the operator for contact with the inner face of the 10 pail 1 by manipulation of the bolt 22.

Thus the frame 10 may be easily and quickly attached or detached, the various slots in the bolted parts enabling adjustment of the parts to the most effective positions 15 for firmly anchoring the frame to the pail while enabling ready detachment thereof.

Each end plate 11 of frame 10 is strengthened by a lateral flange 30, and each end plate is provided with a slot 31 through 20 which extends the shaft 32 of a roller 33. The roller 33 will be referred to hereinafter as the fixed roller since its movement is limited to revolving and to very slight bodily movement along the slots 31. The 25 shaft 32 of the fixed roller is journaled at each end in a collar 34, which is carried by a rod 35 extending forward from the sleeve bearing and passing through an aperture in the respective flange 30. A spring 36 is 30 coiled about each rod 35 and tensioned between the respective flange 30 and the respective sleeve bearing 34, so as to press the sleeve bearing rearward, whereby the fixed roller 33 is held normally with its shaft 32 35 at substantially the rear extreme of slots 31, the roller 33 being however free to be bodily shifted forward by sufficient stress, such as may be produced either by hard sections of a mop or by contact of the co- 40 operating roller in movements hereinafter to be described.

Pivoted at 38 to the frame 10 below and in the rear of one end of fixed roller 33 is an angle plate 39 whose upstanding flange carries eyes 40 between which is arranged the eye 41 of a hinge for the movable roller 42. The eye 41 is of less length than the space between the eyes 40 and the pintle 43 which connects the several eyes is surrounded in 50 the two spaces between the ends of eye 41 and the eyes 40 by the coils of a spring 44. The intermediate portion of the material of which spring 44 is made is formed into a loop 45 which is extended beneath the shaft 46 of movable roller 42 so as to stress the shaft upwardly. The spring 44 is sufficiently tensioned to lift the roller 42 when the roller is free to move under the action of the spring. Upstanding from the eye 41 55 is a bracket carrying a sleeve 47 in which the adjacent end portion of shaft 46 is journaled. For detachably locking the roller 42 to the slot 47, an annular groove 48 is formed in the shaft 46 at a point within the sleeve and a set screw 49 is threaded through

the sleeve 47 so as to extend into the groove 48 during operation, and thereby allow free rotation of roller 42 while restraining the roller against longitudinal shifting. Thus the roller 42, when the end opposite journal 46 is free, may be swung both vertically and horizontally so as to take the position indicated in dotted lines in Figure 5 or the position indicated in dotted lines in Figure 2. The easy introduction of a mop between the 70 rollers is thus insured. It is to be noted that in structures where the roller 42 fits very closely to roller 33, the horizontally swinging movement on the pivot 38 may cause the pivoted end portion of roller 42 80 to strike the adjacent end portion of roller 33 and force the latter roller against the pressure of springs 36 but, as the pivot 38 is substantially at the rear end of plate 39 the movement of roller 42 horizontally will be almost wholly in a direction away 85 from roller 33 and whatever contact may occur even in a closely fitting structure will be but very slight.

The end portion of the shaft of roller 42 opposite journal 46 is extended outward and bent to form an operating crank or handle 50, a portion of the shaft extending beyond roller 42 a distance horizontally sufficient to cause the crank 50 to lie beyond the side of the pail and beyond the brackets engaging the pail. This horizontally extending portion of the shaft serves also as a journal when the roller 42 is in operation. To accommodate movement of the extended portion of the shaft of roller 42 to and from a horizontal position, the end plate 11 opposite to the pivoted end of roller 42 is formed with a slot 51 opening through the upper edge of the said side plate and extending downwardly a distance sufficient to allow the extended portion of the shaft of roller 42 to move to and from a horizontal position through the said slot 51. The shaft finds bearing in the lower terminus of the slot 51, and to avoid the necessity for manually retaining the shaft in its lowered position, a detent 52 is arranged to overhang the shaft when in its lowered position. Said detent 52 consists of a latch plate pivoted 100 at 53 to the adjacent side plate 11 substantially in line with and beneath the slot 51. The latch plate is shaped to extend about and overhang the shaft when the shaft is 105 in its lowermost position, the upper portion of the latch plate being provided with an operating handle 54, and the lower portion of the plate, beneath the pivot 53, is weighted, as indicated at 55, so that when the latch plate is left free it normally assumes the position indicated in Figure 4, and when it is desired to release the movable roller the operator grasps the handle 54 and moves the latch plate to the position indicated in dotted lines in Figure 4. 110

When the roller has thus been released and is being returned to its horizontal position, the latch plate will have dropped back to its normal position as indicated in full lines 5 in Figure 4, and, therefore, the exposed edge of the upper portion of the latch plate is rounded off so that the operator may merely force the crank or handle 50 downward, and as the extended shaft strikes the rounded 10 portion of the latch plate 52, the plate will be cammed out of the way, swinging on its pivot 53. As soon as the shaft has reached its lowermost position, the weight 55 will automatically return the latch plate to its 15 normal position so that it will overhang and lock the shaft in its horizontal position.

In operation, when the parts are in the 20 position seen in Figure 1 and in full lines in Figure 2, the operator approaching with 25 a mop to be wrung grasps the handle 54 of latch plate 52 and swings the plate to the position seen in dotted lines in Figure 4. Thereupon, the spring 44 lifts the roller 42 to an upright or raised position, and if the operator is in a hurry or does not wait for the 30 roller to reach the upright position, but strikes it laterally as it is rising, it thereupon swings to the position indicated in dotted lines in Figure 2. The rollers are then so separated as to enable the easy introduction 35 of the mop between them, and this position has been produced with little or no effort on the part of the operator and by the use of only one hand. The rollers being in this 40 position, the mop is introduced between them, the handle of the mop being held by one hand of the operator while the free hand of the operator grasps the handle 50 and swings the roller 42 back to its horizontal position in operative relation to roller 33. The 45 latch 52 locks the roller 42 in its operative position and then the operator may either turn the crank 50 for wringing his mop or may merely pull the mop upward between the rollers. Of course, the operator will be standing upon the treads 5 while these operations are being carried out.

The roller 42 is provided with means for 50 effecting increased gripping action on a mop or other article disposed between the wringer rolls and being operated upon. To this end, roller 42 is formed with longitudinal slots 56, the slots being preferably formed by slitting the material of the roller 55 and turning back flanges 57, each slot 56 being bordered continuously by its flange 57,

so that, although the roller 42 is preferably formed of metal (usually seamless tubing), the slots 56 do not present cutting edges. The edges of the slots 56 are rounded, as clearly seen in Figure 11, and yet the slots are of sufficient width to allow material between the rollers to be pressed somewhat into the slots. Thus the roller 42 effectively grips such material and forces it between the rollers during the wringing operation.

What I claim is:—

1. In wringing apparatus, the combination, with a frame adapted to be mounted on a scrubbing pail, of a roller rotatably carried by the frame, a co-operating, movably-mounted roller, a pivotally mounted journal bearing for the second-mentioned roller, and a pivotally mounted support for said journal bearing.

2. In a wringing apparatus, the combination, with a frame adapted to be mounted on a scrubbing pail, of a roller rotatably carried by the frame, a co-operating, movably-mounted roller, a pivotally mounted journal bearing for the second-mentioned roller, a pivotally mounted support for the journal bearing, and a spring interposed between said support and journal bearing stressed to move said bearing and thereby to move the movably mounted roller away from the first-mentioned roller when released.

3. In wringing apparatus, the combination, with a frame adapted to be mounted on a scrubbing pail, of a roller rotatably carried thereby, a co-operating roll, a plate hinged to the frame to swing horizontally, and a leaf hinged to the plate to swing vertically, the leaf having a journal bearing in which the co-operating roll is journaled, whereby the co-operating roll is free to swing horizontally and vertically on the frame.

4. In wringing apparatus, the combination, with a frame adapted to be mounted on a scrubbing pail, of a roller rotatably carried by the frame, a co-operating, movably-mounted roller, a pivotally mounted journal bearing for the second-mentioned roller hinged to swing vertically, and a pivotally mounted support for said journal bearing hinged to swing horizontally.

In testimony whereof I affix my signature.

SIMEON C. LAWLOR.
